UNITED STATES PATENT OFFICE.

JOHN H. SMITH AND GEORGE J. KENGEL, OF DETROIT, MICHIGAN, ASSIGNEES
TO ECLIPSE INTERCHANGEABLE COUNTERBORE COMPANY, OF DETROIT,
MICHIGAN, A CORPORATION OF MICHIGAN.

COUNTERBORING TOOL.

Application filed December 14, 1921. Serial No. 522,234.

To all whom it may concern:

Be it known that we, JOHN H. SMITH and GEORGE J. KENGEL, both citizens of the United States of America, residing at Detroit, in the county of Wayne and State of Michigan, have invented certain new and useful Improvements in Counterboring Tools, of which the following is a specification, reference being had therein to the accompanying drawings.

This invention relates to counterboring tools and the invention consists primarily in a provision for readily withdrawing the end portion of a bolt, threaded into a tool holder for securing a cutter to the holder in case said bolt becomes broken through overstrain, and furthermore the invention consists in a novel interlocking relation between tool and holder, for establishing a drive.

20 In the drawings:—

Figure 1 is a view of the improved tool in elevation;

Figure 2 is an axial sectional view of the same;

25 Figure 3 is an end view of the tool holder;

Figure 4 is a view in side elevation of the portions of the cutter which is adapted to have driving and aligning engagement with the holder;

30 Figure 5 is a plan view of said portions;

Figure 6 is a fragmentary sectional view corresponding to the lower portion of Figure 2 but showing a construction eliminating a pilot member.

35 In these views the reference character 1 designates a rotative tool holder having the usual tapered end portion 1^a for engaging a corresponding socket element (not shown).

40 2 is a counterboring cutter having the usual end teeth 2^a. 3 is a bolt functioning to secure the cutter 2 to the holder 1 and having a head 3^a seating centrally against the cutting face of the cutter 2 and functioning as a pilot member. Instead of directly engaging

45 a shank of the bolt 3 with an axially tapped hole in the holder 1, as is common in the art, the invention provides an exteriorly and interiorly threaded bushing 4 which is engaged in an axially tapped opening 5 of the holder and the shank of the bolt fits into

50 said bushing, engaging the interior threads thereof. Thus in case of the bolt breaking

through any cause, the end portion of said bolt engaging in the holder may be readily removed by taking out said bushing. The 55 bushing is adapted for ready removal by forming diametrically opposed notches 6, for engagement by a suitable spanner wrench. When the bolt 3 breaks the fracture usually occurs in close proximity to the 60 holder 1, so that the projecting portion of said bolt is not of sufficient extent to be readily gripped for the purpose of removal. Under such conditions, the broken end portion of the bolt presents a problem which 65 has heretofore been solved only at considerable expense. The use of the described bushing however permits a broken piece of bolt to be removed without difficulty or loss of time.

70 A further feature of the present invention is a novel means for establishing a drive from the tool holder to the cutter. Thus upon its holder-engaging extremity the cutter is formed with a convex key 6 having 75 two opposed plain faces 6^a. This key is snugly engageable in a correspondingly shaped socket 7 milled in the end face of the holder 1. While key and socket drive connections have heretofore been employed, the 80 sockets have had the nature of a groove, cutting completely across an end face of the holder or cutter. Applicant however by use of the described construction leaves an unbroken marginal portion of the end face of 85 the holder to provide a seat for the opposed end face of the cutter. This permits the cutter to be seated very firmly and accurately upon the holder and furthermore the holder (or cutter) is not weakened by extending a groove or channel entirely across 90 the end face thereof.

To center the cutter perfectly with respect to the holder there is provided the cylindrical boss 8 centrally projecting from the 95 key 6 and engageable snugly in a correspondingly shaped extension 9 of the socket 7.

An important advantage derived from the described construction lies in the fact that 100 a variety of bushings 4, differing as regards their interior diameters may be employed with a given holder 1, thus permitting various diameters of bolts 3 to be employed with

the holder, and increasing the range of utility of the tool through this interchangeability.

The described construction furthermore presents a decided advantage over the majority of counterboring tools, in that the drive to the cutter is established in relatively close proximity to the cutting teeth, which relation is conducive to strength. It is a further feature of the described construction that the driving means formed by the key 6 is practically independent of the centering boss 8.

While the described construction is peculiarly advantageous as applied to a counterboring tool, it will be understood that the invention is not limited in its scope of such an application.

When the head of the bolt 3 is not required to function as a pilot said head may be countersunk below the teeth of the cutter as indicated at 3^b in Figure 6.

What we claim as our invention is:—

1. In a boring tool, the combination with a cutter and a holder therefor having abutting end faces, of a drive key projecting from said end face of one of said members, having a pair of opposed plane faces substantially parallel to the axis of said member, the other member being formed with a correspondingly shaped socket engaged by said key, and having a lesser diametrical extent than said member, of a cylindrical boss pro-

jecting from said key and axially engaging the socketed member to relatively center the two members.

2. In a boring tool, the combination with a cutter and a holder therefor, said cutter and holder having abutting end faces, of a convex key projecting from one of said end faces, said key having a pair of opposed plane faces substantially parallel to the axis of said member and having a cylindrical boss projecting from said key, the other of said members having a socket snugly receiving said key and having a lesser diametrical extent than that of said member, said socket having a cylindrical extension for receiving said boss for relatively centering the cutter and holder and means extending centrally through the cutter engaging the holder to secure the cutter thereupon.

3. In a boring tool, the combination with a cutter and a holder therefor having abutting end faces, of a drive key projecting from said end face of one of said members, the other member being formed with a correspondingly shaped socket engaged by said key, and a cylindrical boss projecting from said key and concentrically engaging the socketed member to relatively center the two members.

In testimony whereof we affix our signatures.

JOHN H. SMITH.
GEORGE J. KENGEL.
